UNITED STATES PATENT OFFICE.

HARLEY S. BUSBY, OF WASHINGTON, IOWA, ASSIGNOR TO WESTERN HOG OILER CO., INC., OF WASHINGTON, IOWA, A CORPORATION OF IOWA.

HEATER.

1,328,419.

Specification of Letters Patent.

Patented Jan. 20, 1920.

Application filed October 11, 1916. Serial No. 124,941.

To all whom it may concern:

Be it known that I, HARLEY S. BUSBY, a citizen of the United States of America, and resident of Washington, Washington county, 5 Iowa, have invented a certain new and useful Improvement in Heaters, of which the following is a specification.

My invention relates to an improvement in heaters, and particularly to that type of 10 heater which is designed for use in heating small out-buildings or may be submerged in the water of the ordinary stock watering tank to not only prevent the same from freezing but to keep the water at a constant 15 temperature during the severest weather.

An object of my invention is to provide a 20 heater which is very efficient in operation and one whose construction is simple and durable and in which kerosene may be used as a fuel thus avoiding the labor and danger 25 of fire incident to the use of wood or coal, as fuel as in other forms of burners.

These and other objects of my invention will be more readily understood by having 30 reference to the accompanying drawing in which I have illustrated one embodiment of my invention.

Figure 1 is a side elevation partly in section of a heater embodying the features of 35 my invention;

Fig. 2 is a sectional view taken on the line 2—2 of Fig. 1 looking in the direction of the arrows; and

Fig. 3 is a sectional view taken on the line 35 3—3 of Fig. 1 looking in the direction of the arrows.

In the drawings I have illustrated a heater comprising the cylindrical body portion 4 which may be made of plate steel and 40 which is provided with a heavy cast metal base 5, secured thereto and made a part thereof by having these two parts molded or fused together in any desirable manner whereby the connection or joint is rendered 45 water tight. This base 5 is of sufficient weight to cause the heater to sink to the bottom of a stock watering tank, and is provided with suitable lugs or feet 6 for supporting the heater and which operate to hold 50 the same a slight distance from the bottom of the watering tank when the heater is employed in such connection whereby free circulation of water is permitted about the heater. A suitable cover 7 is fitted on the 55 top of the cylindrical body 4, which top is

provided with a sliding lid 8. Extending upwardly from the cover 7 is a suitable smoke flue 9, which is provided at its upper end with a draft cap 10, of any suitable construction, which prevents any possibility of 60 back draft and also prevents the heat from escaping through the smoke flue.

As clearly shown in Fig. 1, the base 5 extends to one side of the cylindrical body 4 and supports the intake draft pipe 11. This 65 draft pipe is provided with a suitable hood 12, which hood is provided with a downwardly extending flange 13 which fits over the draft pipe and is provided with inwardly extending lugs 14, which rest on top of 70 the draft pipe and support the cap a short distance above the upper end of the pipe. By this construction a suitable supply of air may be admitted to the draft pipe but the same is protected from rain or snow. 75

Passing through the center of the draft pipe 11 is a suitable feed pipe 15 which pipe carries at its upper end a suitable tank 16. A sight dropping feed valve 17 is provided in the pipe 15 by means of which the rapid- 80 85

ity of flow of oil from the tank through the feed pipe can be regulated.

At its lower end the feed pipe is secured by a suitable elbow 18 to the laterally extending pipe 19, which in turn is connected by 85 the elbow 20 to the upwardly extending feed tube 21 which extends through the center of the burner plate 22. This burner plate is mounted on a suitable flange formed in the base 5 and consists of a circular plate of refractory material provided with a downwardly extending cone-shaped central portion 23 through which the feed tube 21 extends. This conical-shaped portion of the burner forms a suitable recess for 90 the reception of a wick 24 of asbestos or other suitable absorbent material. The burner plate 22 is provided with two square openings 25, located on opposite sides of the central conical portion, and mounted on top 95 of this burner is a hollow arc-shaped cap 26 forming a combustion chamber, which cap is provided with two openings which engage with the square openings 25 in the burner plate and with a central opening 27 immediately above the central portion of the burner plate. 100 105

It is thought that the operation of the burner will be readily apparent. The valve 17 is first opened so as to permit the oil to 110

pass from the tank 16, through the feed pipe 15, and thence to the burner plate 22, where it saturates the wick 24. A lighted match is then dropped through the opening 5 covered by the lid 8 onto the wick and the cap 26 is then placed in position. The flame can then be regulated by adjusting the valve 17 so as to vary the flow of oil. The air to support the combustion is drawn through 10 the intake pipe 11, thence through the base and then passes through the two square openings 25 in the burner, through the cap 26, and is thus directed to the flame at the center of the burner. From this construction 15 it will be seen that a very efficient air supply is obtained as the only exit for the air from the base is through the square openings in the burner plate and through the cap 26 by which means the air is carried 20 directly to the top of the flame. It will be noticed that the upper end of the feed tube 21 is reduced in cross-section. With this construction, the tip of this tube becomes heated sufficiently in operation to vaporize 25 the fuel as it is ejected from the feed tube thereby insuring more complete combustion.

A further advantage of my construction is that the feed pipe for the oil passes through the air intake pipe. Thus the cool 30 air passing, through this pipe, tends to maintain the oil feed cool and thus prevents the oil from vaporizing until it strikes the tip of the feed tube 21. Furthermore by reason of the dome in the center of the cap I 35 obtain a more even and steady flame and avoid any flickering. This is due to the fact that the air passing upward through the square openings 25 in the burner is directed toward the center of the cap and 40 swirls about in the dome, thus breaking the direct draft over the top of the flame and

preventing any flickering of the flame which would be caused by such a draft.

It will thus be seen that I have devised a very efficient form of heater and one in 45 which the flame can be very easily regulated and also one in which efficient combustion is insured. Also the construction is such that very little heat escapes through the smoke pipe 9, thus more efficient heating 50 effects are obtained.

While I have illustrated and described one particular embodiment of my invention, it will be understood that I do not wish to be limited to the exact construction shown 55 and described, but that various changes and modifications may be made without departing from the spirit and scope of my invention.

What I claim as my invention is:

In a heater, a base, a fuel oil burner mounted in said base, said burner consisting of a plate having laterally disposed air openings, a fuel-pipe passing through the central portion of said plate, and having 65 a reduced tip so that the walls are sufficiently thin so as to become heated to a degree sufficient to vaporize the fuel emerging therefrom, an arch-shaped air pipe mounted on said plate having terminal openings 70 engaging with said laterally disposed openings and having a central circular opening adjacent the upper end of said fuel pipe, said air pipe being also provided with a cylindrical dome-shaped portion immediately above said fuel-pipe.

Signed by me at Washington, Iowa, this 7th day of October, 1916.

HARLEY S. BUSBY.
